UNITED STATES PATENT OFFICE.

HENRY RICHARDSON, OF CHICAGO, ILLINOIS, AND WILLIAM LIPPERT, OF KENOSHA, WISCONSIN; SAID LIPPERT ASSIGNOR TO SAID RICHARDSON.

WIRE FABRIC.

1,247,721.

Specification of Letters Patent. Patented Nov. 27, 1917.

Application filed December 9, 1914. Serial No. 876,265.

To all whom it may concern:

Be it known that we, HENRY RICHARDSON, a subject of the King of Great Britain, residing at Chicago, in the county of Cook 5 and State of Illinois, and WILLIAM LIPPERT, a citizen of the United States, residing at Kenosha, in the county of Kenosha and State of Wisconsin, have invented certain 10 new and useful Improvements in Wire Fabrics, of which the following is a specification.

This invention relates in general to improvements in wire link fabrics of that type used extensively to form bed and couch bottoms, and pertains more particularly to a 15 type of such fabrics which is made in comparatively light wire, the requisite strength being secured through the avoidance of unsecured end connections of the links in the 20 line of longitudinal strain. The general object of the invention is to provide an improved, simple and strong link fabric of a light wire type, and one which will readily lend itself to manufacture by comparatively 25 simple and easily performed machine operations.

The bent wire link forming the basis of our present fabric employs a two-ply longitudinal tension member and an integral two-ply laterally extending cross-arm that serves 30 to flexibly connect adjacent longitudinal strands of the fabric. Heretofore, so far as we are aware, in fabrics employing a two-ply longitudinal body or tension member 35 and a two-ply cross-arm, the latter has been composed of the two end portions of the wire which forms the link, the free ends of these end portions being bent to form parallel independent hooks which engage a laterally 40 adjacent link of the fabric. In a companion application filed simultaneously herewith, Serial No. 876,264, we have disclosed a construction wherein the two-ply cross-arm is formed from one end portion of the wire of 45 the link bent or folded upon itself with the free end of that portion of the wire forming the cross-arm secured to the body member of the link, and in such construction we have shown the outer end of the cross-arm

formed as a U-bend or loop and passed 50 through or around a portion of a laterally adjacent link to provide a flexible connection between adjacent longitudinal strands. Our present construction employs the same broad feature of a two-ply cross-arm formed 55 wholly from one end portion of the wire of the link, but the outer end of the cross-arm, instead of looping around or through an element of an adjacent link, is bent downwardly and inwardly forming a two-ply 60 hook, the limbs of which are integrally connected at the outer end of the hook, and which hook engages an adjacent link to form a flexible connection therewith, the free end of said hook being preferably given a re- 65 entrant formation to prevent the hook from slipping out of place, this construction being especially useful in fabrics intended for folding couch bottoms. Such a construction of a two-ply cross-arm and terminal hook 70 is superior to a construction wherein the two limbs of the cross-arm and terminal hook are independent of each other, since the two limbs of the cross-arm mutually reinforce each other through their integral 75 connection at the free end of the hook, and the hook itself is superior to a two-ply hook having unconnected limbs for the reason that, in case of unequal tension on the two limbs of the hook, any tendency to yield on 80 the part of the limb receiving the greater tension is resisted by the companion limb through the integral connection between the limbs.

For the purpose of end-to-end connection 85 of the links, one end of each link may be formed by a simple U-bend of the wire, while the other end may be variously shaped to provide a cooperating interlooping member. This latter may take the form of a 90 two-ply substantially vertical loop, or a single vertical loop and a downwardly and laterally bent offset, or a pair of downwardly and laterally bent offsets; the free end portion of the wire that is not used in the 95 formation of the cross-arm being preferably clenched or otherwise strongly secured to the body portion of the link. The outer hooked

end of the cross-arm may embrace the body portion of an adjacent link, or it may hook through a laterally projecting eye on the latter, or it may be otherwise flexibly connected to a laterally adjacent link within the purview of the invention.

In the accompanying drawings we have illustrated our invention as embodied in a considerable variety of specifically varying forms, all of which, however, embody the principle of the invention, and referring thereto—

Figures 1, 4, 7, 10, 13, 16, 19 and 22 are fragmentary top plan views of several slightly varying forms of our fabric;

Figs. 2 and 3 are enlarged sectional detail views on the lines 2—2 and 3—3 of Fig. 1;

Fig. 3^a is an enlarged perspective view of the outer end portion of the cross-arm, looking in the direction of the arrow 3^a of Fig. 1, more particularly illustrating the reentrant form of hook preferably employed.

Fig. 5 is an enlarged sectional detail view on the line 5—5 of Fig. 4;

Fig. 6 is an enlarged perspective view looking in the direction of the arrow 6 of Fig. 4;

Fig. 8 is an enlarged sectional detail view on the line 8—8 of Fig. 7;

Fig. 9 is an enlarged perspective view looking in the direction of the arrow 9 of Fig. 7;

Fig. 11 is an enlarged sectional detail view on the line 11—11 of Fig. 10;

Fig. 12 is an enlarged perspective view looking in the direction of the arrow 12 of Fig. 10;

Figs. 14 and 15 are enlarged sectional detail views on the lines 14—14 and 15—15 of Fig. 13;

Fig. 17 is an enlarged sectional detail view on the line 17—17 of Fig. 16;

Fig. 18 is an enlarged perspective view looking in the direction of the arrow of Fig. 16;

Fig. 20 is an enlarged sectional detail view on the line 20—20 of Fig. 19;

Fig. 21 is an enlarged perspective view looking in the direction of the arrow 21 of Fig. 19;

Figs. 23 and 24 are enlarged sectional detail views on the lines 23—23 and 24—24 of Fig. 22.

In all of the several embodiments of the invention illustrated, the individual link or unit is formed from a single piece of wire so bent as to provide a two-ply body or tension member 5, or 5', the limbs of which are united at one end by a simple U-bend 6. In the form shown in Figs. 1 to 3 inclusive, the wires forming the two limbs of the body member 5 are, at the opposite

end of the U-bend 6, bent downwardly and thence inwardly and upwardly, forming a 65 terminal two-ply loop comprising the limbs 7 and 8 designed for interlooping engagement with the U-bend 6 of an endwise adjacent link, in the manner clearly shown in Fig. 2. The wire forming the limb 8 of the terminal loop is carried across and secured to the body member at 9. The wire forming the terminal limb 7 of the terminal loop is extended across the body member and folded or bent backwardly upon itself, 75 thus forming a two-ply cross-arm 10, the free end of the portion of the wire forming this cross-arm being carried across and secured to the body member at 11. This construction provides a two-ply cross-arm that is formed wholly from one of the end portions of the wire of the link, and the two limbs of which are integrally joined at their outer end. This outer end portion of the cross-arm is bent downwardly and inwardly 80 forming a two-ply hook 12, and the extreme end of this hook is preferably given a reentrant bend, as clearly indicated at 12' in Figs. 3 and 3^a, thereby effectively closing the entrance end of the hook and preventing 85 displacement of the hook from the part engaged thereby. The hook 12 embraces the body member 5 of a laterally adjacent link, preferably between the two limbs of the cross-arm of said laterally adjacent link, as 90 shown in Figs. 1 and 2.

The form shown in Figs. 4 to 6 inclusive differs from that of Figs. 1 to 3 inclusive only in that the terminal loop member 8 is somewhat longer and is brought up and across the body member from the opposite side of the latter as shown at 8', and the end hook of the cross-arm is engaged with the body member 5 directly between the two 95 limbs of the cross-arm.

The construction of Figs. 7, 8 and 9 differs from that of Figs. 1 to 3 inclusive only in that the wire forming the terminal loop member 7, instead of extending over the body member 5, extends beneath said body 100 member as shown at 13, and continues thence to form the cross-arm 10.

Figs. 10, 11 and 12 show a construction wherein the portion of the wire forming the vertical terminal loop member 8 is extended in 115 one direction to form a lateral eye 14, the free end of which is anchored to the body member at 15, while the wire forming the terminal loop member 7 is extended in the opposite direction, as shown at 16 to form a 120 cross-arm 10' differing slightly from the cross-arms previously described in that the two limbs lie substantially parallel throughout the full length of the arm. The inner ends of both limbs of the cross-arm engage 125 the body member between the sides of the

eye 14, and the hook 12 of the cross-arm engages the eye 14 of a laterally adjacent link.

The construction of Figs. 13, 14 and 15 closely follows that of Figs. 1, 2 and 3, differing only in that the free end of the terminal loop member 8 is carried across and clenched to the body member in the opposite direction, as shown at 17, and the body member 5' is somewhat differently shaped, the two limbs extending parallel throughout the greater part of the body member and being inwardly offset near the end of the link as shown at 18 to form a stop to prevent displacement of the lower limb 15 of the cross-arm and also a contracted neck which receives the hooked end of an adjacent cross-arm and forms the anchorage for the free end of the loop member 8 and the free end of the wire forming the cross- 20 arm.

In the construction of Figs. 16, 17 and 18, the wire that forms the terminal loop member 7 is carried upwardly and across the neck of the body member 5' as shown at 19, 25 being thence extended to form the cross-arm 10, while the end of the wire forming the terminal loop member 8 is simply bent upwardly substantially into contact with the underside of the neck of the body member as shown at 20 (Fig. 17), and left free. The hooked end 12 of the cross-arm engages the neck of the body member of an adjacent link directly between the inner ends of the limbs of the cross-arm of said adjacent link. 30

The construction of Figs. 19, 20 and 21 dispenses with the terminal loop member 8 of the previously described constructions, substituting therefor a downwardly and laterally offset bend 21, which is extended 35 laterally to form the cross-arm 10. In this case we have shown the terminal loop member 7 as embracing the body member 5 at 22, below the lower limb of the cross-arm; and in this construction the said lower limb 40 of the cross-arm is secured to the body member by passing beneath, thence up and over, and again beneath the body member, completely embracing the latter as shown at 23. 45

In the construction of Figs. 22, 23 and 24, the two limbs of the body member 5 are bent downwardly and laterally in opposite directions as shown at 24 and 25, the portions of the wire being thence extended to form on one side a lateral eye 26, the end 50 of which is clenched to the body member at 27, and on the other side the cross-arm 10. The free end of the wire forming the cross-arm is anchored to the body member at 28, and the hooked end of the cross-arm, instead of engaging the body member, engages 55 the lateral eye 26.

We claim:

1. A wire link fabric including a plurality

of links or units, each composed of a single piece of wire bent to form a body member 65 and a two-ply cross-arm, said cross-arm consisting of an end portion of the wire of the link bent upon itself and terminating at its outer end in a hook; said links being engaged with each other end-to-end to form 70 longitudinal strands of the fabric and having the outer ends of their cross-arms interhooked with the links of an adjacent strand.

2. A wire link fabric including a plurality of links or units, each composed of a single 75 piece of wire bent to form a body member and a two-ply cross-arm, said cross-arm consisting of an end portion of the wire of the link bent upon itself and terminating at its outer end in a two-ply hook, the free end of 80 said end portion of the wire being secured to the body member; said links being engaged with each other end-to-end to form longitudinal strands of the fabric and having the outer ends of their cross-arms interhooked with the links of an adjacent strand. 85

3. A wire link fabric including a plurality of links or units, each composed of a single piece of wire bent to form a two-ply body member with terminal portions adapted for 90 interlooping end connections and a two-ply cross-arm, said cross-arm consisting of an end portion of the wire of the link bent upon itself and terminating at its outer end in a two-ply hook, the free end of said end 95 portion of the wire being secured to the body member; said links being interlooped with each other endwise to form longitudinal strands of the fabric and having the outer ends of their cross-arms interhooked 100 with the links of an adjacent strand. 100

4. As a new article of manufacture, a wire fabric link consisting of a single piece of wire bent to form a body member and a two-ply cross-arm, said cross-arm consisting of an end portion of the wire of the link bent upon itself and terminating at its outer end in a two-ply hook, and the free end of 105 said end portion of the wire being secured to the body member. 110

5. As a new article of manufacture, a wire fabric link consisting of a single piece of wire bent to form a two-ply body member with terminal portions adapted for interlooping end connections in a strand and a 115 two-ply cross-arm, said cross-arm consisting of an end portion of the wire of the link bent upon itself and terminating at its outer end in a two-ply hook for connection to an adjacent strand, and the free end of said 120 end portion of the wire being secured to the body member.

6. A wire link fabric including a plurality of links or units, each composed of a single piece of wire bent to form a body member 125 and a two-ply cross-arm, said cross-arm con-

sisting of an end portion of the wire of the link bent upon itself and terminating at its outer end in a two-ply hook, the free end of said end portion of the wire being se-
5 cured to the body member; said links being engaged with each other end-to-end to form longitudinal strands of the fabric and having the outer ends of their cross-arms hooked over the body members of laterally ad-

jacent links between the limbs of the two-ply cross-arms of said laterally adjacent links. 10
